UNITED STATES PATENT OFFICE

151,107

DESIGN FOR A FISH LURE

Ray A. Vaughn, Cheboygan, Mich.

Application April 19, 1946, Serial No. 128,778

Term of patent 3½ years

(Cl. D31—4)

To all whom it may concern:

Be it known that I, Ray A. Vaughn, a citizen of the United States, residing at Cheboygan, in the county of Cheboygan and State of Michigan, have invented a new, original, and ornamental Design for a Fish Lure, of which the following is a specification, reference being had to the accompanying drawing, forming a part thereof, in which:

Fig. 1 is a side elevational view of a fish lure, embodying my new design;

Fig. 2 is a top view; and

Fig. 3 is a front elevational view.

The fish lure is ornamented by the application of spirally disposed stripes of contrasting colors on the front portion thereof, the colors indicated

in the drawing for the purpose of illustration being red, white and blue.

I claim:

The ornamental design for a fish lure, substantially as shown and described.

RAY A. VAUGHN.
